Patented January 19, 1904.

UNITED STATES PATENT OFFICE.

LEMUEL R. HOPTON, OF NEW YORK, N. Y., ASSIGNOR TO THE OXLEY ENOS COMPANY, OF NEW YORK, N. Y., A CORPORATION OF NEW YORK.

DESIGN FOR A GLOBE-SUPPORT FOR INCANDESCENT-LIGHTING APPARATUS.

SPECIFICATION forming part of Design No. 36,743, dated January 19, 1904.

Application filed April 24, 1903. Serial No. 154,188. Term of patent 3½ years.

To all whom it may concern:

Be it known that I, LEMUEL R. HOPTON, a citizen of the United States, residing at New York, in the county of New York, State of New York, have invented a certain new, original, and ornamental Design for a Globe-Support for Incandescent-Lighting Apparatus, of which the following is a full, clear, and exact description.

10 The drawing is a perspective view of a globe-support for incandescent-lighting apparatus

embodying the ornamental form and outline of my design.

What I claim is—

The ornamental design for a globe-support 15 for incandescent-lighting apparatus as herein shown.

LEMUEL R. HOPTON.
